ADJUSTABLE HEATING ELEMENT SUPPORTS
Leroy C. Hanson, Elmhurst, Ill., assignor to Ferro
Corporation, a corporation of Ohio
Filed June 5, 1962, Ser. No. 200,102
2 Claims. (Cl. 219—526)

This invention relates to a heating unit assembly, and more particularly to a readily adjustable means for mounting and supporting the heating element of a heating unit assembly on a range top or the like having various size surface openings.

Heating elements are mounted on an electric range by legged spiders as is well known in the art. However, electric ranges presently have various size elements and a different size spider is used to support each element, making the construction of the heating unit assembly both difficult and costly. It is therefore desirable to have element supporting spiders which may all be manufactured alike, but include means therein to provide a simple adjustment in the length of the spider legs to fit various size range openings. This adjustment will also allow for the minor size variations in the range openings which are a result of manufacturing tolerances during construction.

It is an object of the present invention to provide a new and improved device of the type described above.

Another object of the present invention is to provide a supporting spider having at least one leg thereof infinitely adjustable between its limits by means of a screw device on said leg.

A further object of the present invention is to provide a supporting spider having at least one leg thereof adjustable by means of scored, break-off portions at the outer end of the leg.

Still another object of the present invention is to provide a supporting spider having at least one leg thereof adjustable by means of a bendable portion at the outer end of the leg.

Other objects and advantages will become readily apparent from the following detailed description taken in connection with the accompanying drawing, in which:

FIG. 1 is a plan view of an embodiment of the invention shown in its environment with the heating element and a portion of a range top;

FIG. 2 is a vertical sectional view taken generally along the lines 2—2 of FIG. 1;

FIG. 3 is an enlarged fragmentary sectional view taken generally along the line 3—3 of FIG. 1;

FIG. 4 is a perspective view of a second embodiment of a spider removed from the heating unit assembly; and

FIG. 5 is a perspective view similar to FIG. 4 of a third embodiment of the invention.

While this invention is susceptible of embodiment in many different forms, there is shown in the drawings and will herein be described in detail an embodiment of the invention, together with modifications thereof, with the understanding that the present disclosure is to be considered as an exemplification of the principles of the invention and is not intended to limit the invention to the embodiments illustrated. The scope of the invention will be pointed out in the appended claims.

Referring now to the drawing, FIG. 1 illustrates a plan view of one embodiment of the spider support 10 shown in relation to its surrounding elements. The heating unit assembly generally shown at 11 includes a sheathed coil 12 and the supporting spider 10. The coil 12 is movably attached to the spider 10 as by attaching elements 13 connected to the coil 12 and passing through apertures 14 in the spider 10. Electrical contacts 15 provide current to heat the coil 12 as is well known in the art.

As shown in FIG. 3, the range top 16 has an opening

2

therein and a drip pan 17 is positioned within this opening.

As is well known in the art, a support spider 10 is used to hold the heating element in position in the opening of the range top 16. The spider 10 is formed from three similarly shaped pieces, A, B and C, and all three embodiments shown in this disclosure will be described similarly except for the adjustable ends thereon. The piece A of the spider is exactly similar in all three embodiments and includes the apertures 14 on the leg thereof, a curved connecting portion *a* and an attaching flange *a'*. At the outer end of this leg a dog 18 is formed. This dog, as shown in FIG. 2, fits into aperture 19 of a vertical side of range top 16 and firmly positions the spider within the range opening yet permits removal of the spider 10 and heating element to allow cleaning of drip pan 17. The adjustable ends of the spider 10 are shown in the three preferred embodiments and these will be described in detail hereinafter.

The first embodiment (FIGS. 1 and 3) includes a bracket 20 permanently affixed to the outer end of the legs of spider 10 as by welding. This bracket includes apertures 21 and 22 and screw member 24 passing through said apertures. In operation the screw members 24 are adjusted to create the proper length on the outer ends of the spider 10 so that the spider will be firmly but releasably held in the range top. As shown in FIG. 3 the head 25 of screw member 24 rests on the lower flange of range opening 16 and supports the heating unit assembly in its proper position.

The second embodiment shown in FIG. 4 is similar except for the adjustable means at the outer end of spider 10. These adjustable means consist of scored portions 30 and 31. Of course there could be any number of scored portions on the outer end of the spider leg, but only two are shown here for simplicity. When it is desired to adjust the length of the spider legs so that the spider 10 will fit firmly in the range opening, the necessary portions 30 or 31 are broken off and the spider leg is thus shortened to its necessary length for properly positioning the spider and heating unit assembly 11.

The third embodiment of the invention shown in FIG. 5, again is similar to the others, except for the adjustable ends of the spider legs. This embodiment includes a slot 35 normal to the end of the spider leg with the top portion of the spider leg being shorter as at 36 than the lower portion of the spider leg as at 37. In order to adjust this form of the spider, the longer portion of the spider leg 37 is bent so as to shorten the spider leg the necessary amount so that the spider is firmly yet releasably held in the range top opening.

In all forms of this invention, the lower edge of the spider leg rests on the flange of the range top 16 as illustrated by the screw head 25 in FIG. 3.

Thus it has been shown how three similar members, A, B and C, can be attached together to form a simple, single unit spider 10, and various adjustable means as described hereinabove can be positioned at the outer ends of the necessary spider legs to provide for a supporting structure positioning a heating unit assembly in its proper relationship with a range top, so that the heating unit assembly is firmly held therein, yet is releasably mounted so that it may be removed for necessary cleaning and maintenance.

I claim:

1. A spider for mounting an electric heating element on an electric range having an opening therein to receive said element, comprising: a member having a plurality of radially extending legs, said member having a central portion adapted to be positioned in supporting relationship under the center of said heating element, said member possessing sufficient rigidity and strength to support said

element and a cooking vessel placed thereon, the outer extremity of at least two of said legs being provided with outwardly extending strips integral with the legs and having a height substantially less than the height of the legs, said strips being of less rigidity and strength than the remainder of said legs and being readily bendable whereby to adjust the radial extent of said legs to accommodate openings of different size.

2. The spider of claim 1 in which said strips are scored.
